G. W. TINDALL

SOAP STICK HOLDER

Filed Dec. 29, 1923

FIG. 1.

FIG. 2.

INVENTOR
G. W. TINDALL.

BY *John W. Tindall*

ATTORNEYS.

UNITED STATES PATENT OFFICE.

GEORGE WESLEY TINDALL, OF TORONTO, ONTARIO, CANADA, ASSIGNOR TO C. E. FULFORD LIMITED, OF TORONTO, ONTARIO, CANADA, A COMPANY OF GREAT BRITAIN.

SOAP-STICK HOLDER.

Application filed December 29, 1923. Serial No. 683,383.

To all whom it may concern:

Be it known that I, GEORGE WESLEY TINDALL, a subject of the King of Great Britain, and a resident of the city of Toronto, in the county of York, in the Province of Ontario, Canada, have invented certain new and useful Improvements in Soap-Stick Holders, of which the following is the specification.

10 My invention relates to improvements in soap stick holders, and the object of the invention is to devise a soap stick holder in which the soap stick may be readily inserted in the holder or replaced by a new stick whenever required by the purchaser, and is such as will dispense with the threading of the soap stick and the employment of anyone skilled for the insertion of the stick in the holder, and it consists essentially of the arrangement and construction of parts as hereinafter more particularly explained.

15 Fig. 1 is a sectional view through my holder showing the soap stick in position.

20 Fig. 2 is a perspective detail of a portion of a soap stick and the metal connector cap carried thereby.

In the drawings like characters of reference indicate corresponding parts in each figure.

30 1 indicates a soap stick.
2 is a cap formed of suitable material, the upper portion of which is knurled, as indicated at 3, the intermediate portion threaded as indicated at 4, and the lower portion 35 provided with inwardly stamped spicular projections 5. When the cap is ready for insertion upon the end of a stick, the spicular projections 5 rest flush with the surface of the wall of the cap, and after the soap 40 stick has been inserted within the cap, are forced inward into the soap so as to engage the stick.

45 6 is a cylindrical casing or container for the soap stick, the edge of which is provided with an enlarged portion 7 which is internally threaded.

50 8 is a closing cap for the container 6. The cap 8 is provided with an annular flange 8^x, the periphery of which is preferably knurled, and with an annular inwardly extending flange 9 having an external thread 55 engaging the internal thread of the en-

larged portion 7. The upper portion of the flange 9 is reduced so as to fit within the upper end of the container 6, such portion 55 being inturnedly threaded so as to engage with the threaded portion 4 of the cap 2.

10 10 is a projection or projections extending from the cap 2, being stamped in the metal thereof and fitting into a corresponding depression or depressions 11 in the cap 8. This construction serves to prevent the easy or inadvertent unscrewing of the soap stick cap from the container cap unless forced manually by turning the soap stick 65 cap in the cap of the casing so as to spring the projections 10 out of the depressions 11. The wall of the container 6 is preferably provided with an annular bead 12.

From this description it will be seen that 70 I have devised a very simple device whereby a soap stick may be readily inserted in a container.

It will be understood that the cap 2 is secured upon the soap stick by the manufacturer, a cap being sold with every stick so that all the purchaser has to do is to remove the closing cap 8 of the container, unscrew the old soap stick from the cap, and screw the new soap stick into position.

80 What I claim as my invention is:

1. A soap stick holder comprising a cylindrical casing, a closing cap for the casing, a soap stick cap in which a soap stick is adapted to be permanently inserted, a threaded connection between the soap stick cap and container cap, and interengaging means formed in the soap stick cap and container cap for preventing the inadvertent unscrewing of the soap stick cap from the container 90 cap.

85 2. A soap stick holder comprising a cylindrical casing, a closing cap for the casing, a soap stick cap in which a soap stick is adapted to be permanently inserted, a threaded connection between the soap stick cap and container cap, projections extending from the bottom of the soap stick cap, and depressions formed in the inner face of the container cap into which the aforesaid projections fit when the soap stick cap is in position within the container cap.

100 GEORGE WESLEY TINDALL.
